CLAIM

The ornamental design for an amplifier shaped coffee maker, as shown and described.

DESCRIPTION

FIG. 1 is a front elevational view of a amplifier shaped coffee maker showing our new design;

FIG. 2 is a rear elevational view thereof;

FIG. 3 is a right side elevation view of FIG. 1.

FIG. 4 is a left side elevation view of FIG. 1.

FIG. 5 is a top plan view of FIG. 1.

FIG. 6 is a bottom plan view thereof; and,

FIG. 7 is a top perspective view thereof.

The broken lines in the drawings are included for the purpose of illustration and form no part of the claimed design.
